(57) CLAIM

The ornamental design for an LED-illuminated vehicle steering wheel cover, as shown and described.

DESCRIPTION

FIG. 1 is a front perspective view of a vehicle steering wheel that is covered with an LED illuminated vehicle steering wheel cover showing my new design. The LEDs are operated by an enclosure containing a battery and a switch and that is attached to a surface of a steering wheel enclosure shown by broken lines. The steering wheel enclosure and other wheel structures are shown in broken lines for illustrative purposes only and form no part of the claimed design. FIG. 2 is a front elevational view thereof, the rear side being a mirror image. The enclosure is shown with an electrical cable entering through an inner circumferential opening not shown; and,

FIG. 3 is a right-side elevational view, the left-side being a mirror image.
